Primary Examiner — Eric Goodman*Assistant Examiner* — Jennifer L Rempfer*(74) Attorney, Agent, or Firm* — Clark & Brody(57) **CLAIM**

The ornamental design for a support pillow, as shown and described.

DESCRIPTION

FIG. 1 is a rear top and side perspective view of the support pillow showing a first embodiment;

FIG. 2 is a rear top perspective view thereof;

FIG. 3 is a front perspective view thereof;

FIG. 4 is a left side perspective view thereof;

FIG. 5 is a bottom rear perspective view thereof;

FIG. 6 is a left side front perspective view thereof;

FIG. 7 is a rear top side perspective view showing a second embodiment;

FIG. 8 is a rear top and side perspective view thereof;

FIG. 9 is a front perspective view thereof;

FIG. 10 is a left side perspective view thereof;

FIG. 11 is a bottom rear perspective view thereof; and,

FIG. 12 is a left side front perspective view thereof.

The broken lines represent features that form no part of the claim.
